UNITED STATES PATENT OFFICE

2,205,078

SUCTION CLEANER

Bernard C. Becker, Canton, Ohio, assignor to
The Hoover Company, North Canton, Ohio, a
corporation of Ohio

Continuation of application Serial No. 628,813,
August 15, 1932. This application January 29,
1934, Serial No. 708,893

10 Claims. (Cl. 240—2)

The present invention relates to suction cleaners in general and more particularly to a new and improved suction cleaner embodying means to illuminate the surface covering undergoing cleaning and articles of furniture positioned immediately forward of the cleaner, for the purpose of enabling the operator better to manipulate the machine and to discern foreign material in dark corners etc. which would otherwise escape observation. More specifically the present invention comprises the combination of an electric illuminator and the motor casing of the cleaner, the parts being so constructed as to direct the rays of an electric light embodied therein forward of the cleaner.

The present application is a continuation of application Serial No. 628,813, filed August 15, 1932, now abandoned.

It is an object of the present invention to provide a suction cleaner embodying floor illuminating means. It is a further object to provide a suction cleaner in which electric illuminating means are formed upon the motor casing to illuminate the nozzle and the adjacent covering. These and other more specific objects will appear upon reading the following specification and claims and upon considering in connection therewith the attached drawing to which they relate.

Referring to the drawing in which a preferred embodiment of the present invention is disclosed:

Figure 1 is a side view of a suction cleaner with the present invention embodied therein;

Figure 2 is a bottom view of the upper removable portion of the motor casing with the illuminator embodied therein;

Figure 3 is a cross section through the construction of Figure 2;

Figure 4 is a partial side view of the motor casing similar to Figure 1 with the guard partially broken away.

In the drawing the present invention is shown embodied in a modern suction cleaner the body or housing of which comprises a nozzle 1, a fan chamber 2, and an exhaust outlet 3. To the latter a dirt receptacle 4 is removably attached by suitable securing means 5. The upright cylindrical motor-containing casing 6 is carried by the main casing being positioned immediately above the fan chamber and in the rear of the nozzle 1, a shoulder being formed at the bottom of the casing. The cleaner is movably supported upon front wheels 7 and rear wheels 8, one of each being shown, the latter being provided with means, indicated generally by the reference character 9, by which they can be raised and lowered

to effect the variation in the nozzle height above the surface covering undergoing cleaning.

In the suction cleaner constructed in accordance with the present invention the motor casing 6 is formed of a lower section 11 and an upper section 12. The resulting casing encloses the motor frame 13 which carries the motor brush 14 which is adapted to contact the rotating armature 15 at its commutator. This construction is clearly shown in Figure 1 of the drawing.

Integrally attached to the lower edge of section 12 of motor casing 6 is the floor illuminator guard comprising a hollow body 18 which is formed with an encircling band or collar 16 which seats the lower edge of section 12.

The hollow lamp guard body or visor is open at its rear side, as is the section 12 immediately adjacent thereto. The openings are indicated by the reference character 24 and open to the space within the guard body a space within the section 12 the back of which is defined by an imaginary chord extended between the sides of the openings. Within this enlarged space practically all of the illuminating means are positioned, excepting only the continuations of the current conductors hereinafter described. The visor and casing section 12 are secured together by rivets 17, 17 to form a unitary construction.

The hollow body portion of the lamp guard, being adapted to function as a reflector is trough shaped, the interior thereof being preferably whitened or polished for the purpose of providing better reflecting qualities. Lamp guard 18 is entirely open at its forward side and is so shaped as to direct light beams forwardly and downwardly onto and in front of nozzle 1 confining substantially all light rays to an angle below the horizontal. On one side wall of guard 18 is mounted a cylindrical lamp base receptacle 19 which is shown attached to guard 18 though it may well be formed integrally. Socket 19 is secured in place through being provided with a threaded bolt portion 19a which extends through the guard wall and seats a nut 19b. A light 20 is removably mounted in receptacle 19, the two parts being removably held together by a bayonet-socket relationship indicated at 21. Closely adjacent socket 19 is mounted a switch 22 through which passes one of the current-carrying leads 23, 23 to enable the operator to turn the light 20 on or off. The leads 23, 23 pass from the reflector 18 through the opening 24 and are attached to the motor being provided with suitable screw caps 25, 25 at their inner ends which are adapted to form a part of the

brush mounting 14 and to conduct electric current from that brush to the light.

To protect both the illuminator and articles of furniture with which it may possibly come into contact in the operation of the cleaner a furniture guard of resilient material is provided which encloses the edge of the visor 18, being indicated by the reference character 26.

The illuminator is so formed that it can be attached to a standard motor casing, it being necessary only to remove the casing section 12 from the casing section 11, to provide the opening 24 in its side and then to attach it to the band 16 of the illuminator body. When so attached the guard and lamp are disposed within the limits of the cleaner and do not increase the overall height thereof. The light is protected by the cleaner nozzle from collision with vertical objects, such as table and chair legs and the substantial construction of the guard protects the lamp proper.

I claim:

1. A motor casing cap for a suction cleaner comprising a housing portion closed on one side and open on the other, a collar seating the edge of said housing at its open side and secured thereto, a reflector housing integrally formed on said collar and positioned at the side of said housing, an electric light detachably mounted in said reflector housing, current-carrying leads extending thru said housings and connected to said light, and a switch carried by said reflector housing and in the circuit of one of said current-carrying leads.

2. A floor illuminator attachment for a suction cleaner including a metallic body formed as a housing having one open side and a circular collar formed thereon and extending laterally therefrom, said collar being adapted to seat a circular motor casing, the interior of said housing being finished to function as a reflector and the exterior thereof being protected by an encircling rubber guard, an electric light removably carried in said housing, a manually operable switch carried by said housing and current-carrying leads connected to said light and to said switch and extended thru a side of said housing.

3. A motor casing cap for a suction cleaner comprising a circular housing portion closed on one side and open on the other, a collar seating the edge of said housing at its open side and secured thereto, a reflector housing integrally formed on said collar and positioned at the side of said housing, an electric light detachably mounted in said reflector housing, current-carrying leads extending thru said housings and connected to said light, threaded caps carried by the inner ends of said leads adapted to be connected to motor brushes, and a switch carried by said reflector housing and in the circuit of said current-carrying leads.

4. A headlight for a suction cleaner comprising a recessed body portion formed as a reflector, a bulb socket carried at one end of said reflector, a light bulb removably seated in said socket and displaceable through the open side of said deflector, a switch carried by said body portion having an operating handle positioned exteriorly

of said reflector, a collar formed integrally on said body portion extending rearwardly from said reflector, said collar being formed with an interior shoulder adapted to seat an adjacent motor housing, and conductors connected to said socket and switch extending from said body portion to within said collar and adapted to be connected to a source of electricity.

5. An accessory for a suction cleaner comprising a circular band and a forwardly extending reflector housing, said circular band being adapted to seat on a portion of a motor casing, and having its interior surface counter-sunk to receive a complementary portion of said motor casing and forming an intermediate portion of the said motor casing, and a support for said reflector housing, said reflector housing being adapted to receive and support a source of light and to confine substantially all light rays to angles below the horizontal.

6. A domestic floor-cleaner having an ambulant wheeled frame including an electric motor, a fan-casing and a down-turned suction-nozzle, said motor being of cylindrical form with its axis upright and having a recess in its front side adjacent said nozzle, and an electric lighting device mounted in said recess.

7. A domestic floor-cleaner having an ambulant wheeled frame including an electric motor, a fan-casing, and a down-turned suction-nozzle, said motor having a cylindrical motor-casing formed with a tangential recess, and an electric lighting device of tubular form arranged with its longitudinal axis transverse to the longitudinal axis of the cylindrical motor-casing and partially received in said recess.

8. The combination with a domestic type ambulant suction floor-cleaner including a wheeled fan-casing having a downturned transversely elongated suction-nozzle and a dust-discharge pipe and a suction fan-motor of cylindrical form superimposed upon and carried by said fan-casing with its axis upright and formed in its front side below its top with a recess, of an electric lighting device mounted on said fan-motor below the top of the latter and above the fan-casing and partially received in said recess.

9. The combination with a domestic type ambulant suction floor-cleaner including a wheeled fan-casing having a downturned suction-nozzle and a shoulder above and in rear of said nozzle, and a suction fan-motor superimposed upon said fan-casing above and in rear of said shoulder and having a motor-shaft extending downwardly into said casing, of an electric lighting device recessed in the front side of said fan-motor below the top of the latter and above and in rear of said shoulder.

10. A housing for an electric motor comprising a support portion, a cover portion, and an intermediate portion which overlies the adjacent edges of said support and cover portions and serves to cover the joint, said intermediate portion being formed with a hollow forward extension adapted to receive a light source and so shaped as to direct light rays ahead of said housing.

BERNARD C. BECKER.
